UNITED STATES PATENT OFFICE.

LEVI B. NEWHALL AND FRANK B. NEWHALL, OF LYNN, MASSACHUSETTS,
ASSIGNORS OF ONE-HALF TO J. W. INGALLS & SON, OF SAME PLACE.

MECHANISM FOR CLEANING BOOT OR SHOE UPERS.

SPECIFICATION forming part of Letters Patent No. 368,105, dated August 9, 1887.

Application filed February 17, 1887. Serial No. 228,129. (No model.)

To all whom it may concern:

Be it known that we, LEVI B. NEWHALL and FRANK B. NEWHALL, of Lynn, in the county of Essex and Commonwealth of Massachusetts, have invented certain Improvements in Machines for Cleaning Boot or Shoe Uppers, of which the following, taken in connection with the accompanying drawings, is a specification.

This invention relates to mechanism for cleaning boot or shoe uppers, and the nature thereof is fully described and specifically claimed hereinafter.

Referring to the drawings, which accompany and form a part of this specification, Figure 1 is a plan view of a machine made in accordance with and embodying this invention. Fig. 2 is a side elevation of said machine, made partly in section to illustrate details of construction. Figs. 3, 4, 5, 6 are details to be referred to hereinafter.

The driving-shaft A is mounted in and allowed to be revolved in the frame B B, and on the shaft is a sheath, D, to receive the driving-cord from any suitable driving-pulley. The frame B B has its ends journaled in the supporting-frame E, as shown in Fig. 2. Projecting outwardly from the rear end of shaft A is an eccentric-pin, F, that enters a suitable hole in the block H, and the block H is arranged to permit vertical movement in its supporting standard K, and from this construction the shaft A is given a compound movement. The pin F being eccentric with the shaft A, it follows that when the shaft is revolved either the pin must travel round the center of the shaft or the shaft must travel round the center of the pin, and taking advantage of this, we allow the pin to travel round the shaft during part of the revolution, when it lifts and depresses the block H, as indicated in Figs. 3 and 5, to which end the block H permits the necessary vertical movement in standard K. During the other portions of the revolution the shaft must travel round the pin, and this imparts a lateral vibratory motion to the shaft, as indicated by Figs. 4 and 6, and to permit this the frame B has its ends suitably pivoted in standard E, as shown.

The cleaning-pad is mounted on the forward end of said shaft A. To this end we provide the core a with a central longitudinal bore to receive the shaft A, as indicated in Fig. 2.

This core is preferably composed of wood, and is surrounded by a piece of thick felt, b. This felt projects at either end beyond the core, and recesses are thus formed in which holding and adjusting devices are positioned, which will hereinafter be described. At the end is a re-enforcing sleeve or thimble, w, composed of rubber or similar material. It gives a supporting but yielding quality to the pad at this point, and so prevents the pad from being jammed out of shape. It further serves to shield the end of the shaft and its incident clamps, and so prevents the shoe from being injured if accidentally or otherwise pressed against the end of the pad.

The pad is covered by a piece of plain cotton cloth, d; but we are aware that chamois-skin or other textile fabrics would give good results, though not so economical. To facilitate the adjusting of the fabric onto the pad, and to insure its remaining there, we employ the metallic ferrules e f, which are secured to the core a and are threaded suitably to receive the nuts h k, as shown in Fig. 2. The ferrule e is further provided with an inside thread to engage a thread on the outside of shaft A, and so retain the pad on said shaft while in operation. In adjusting the fabric it is first wrapped about the felt. The edges at one end are put into clamp m and the nut e turned up, as in Fig. 2. The edges of the opposite end are put into clamp n, and thereupon the nut h is moved inward, forcing forward the clamp n, and so stretching the fabric tightly over the pad. It may be further tightened by a similar movement of the clamp n, whenever by use or otherwise it gets loosened.

In operation the upper is held in the hands of the workman and pressed upward under the pad. We are aware that the revolving or the vibrating movement of the pad may be dispensed with; but the pad will not last so long, and will consequently not be so economical as when the compound movement is employed.

We claim—

1. The combination of the core a, the felt b about said core, the fabric-covering d, and means, substantially as described, for holding said fabric, said means being also adjustable to apply tension to the fabric, substantially as described.

2. In a cleaning-pad for boots or shoes, and in combination the core *a*, the felt *b*, the fabric *d*, covering the said felt, the holding devices, substantially as described, for one end of said fabric, and the holding and adjustable devices, as the clamp *n* and screw *h*, substantially as described.
3. In combination, the pad, the fabric *d*, and the clamps *m* and *n*, and screws *h k*, for holding and adjusting the said fabric to the pad, substantially as described.
4. In combination, the core *a*, the felt *b*, surrounding said core and projecting at the ends beyond the core, whereby recesses are formed, the fabric covering the felt, and the holding devices for said fabric situated within the recesses at the ends of the felt-covering, substantially as described.
5. In combination, the shaft, the core *a*, surrounding the same and carried thereby, the cleaning material extending peripherally about the core, and the sleeve or thimble of rubber situated on the end of said core and extending beyond the end of the shaft, substantially as described.
- 20 6. In combination, the core *a*, the yielding cleaning material projecting beyond the said core, and the rubber piece *w* at the end of said core engaging with the projecting cleaning ma-

terial and supporting the same, substantially as described.

7. In a machine for cleaning boot or shoe uppers, the cleaning-pad, a supporting-shaft for the pad, said shaft being pivotally supported, and means, substantially as described, for automatically imparting a rotary and oscillatory movement to said shaft, substantially as described.

8. In a machine for cleaning boot or shoe uppers, the revoluble pad pivotally supported, and means, substantially as described, for automatically imparting a pivotal movement to said pad, substantially as described.

9. The combination of the shaft *A*, the pivoted frame *B B*, means for revolving the shaft, and the mechanism described for giving to the shaft a lateral reciprocating movement, substantially as described.

10. The combination of the core *a*, composed of wood or other suitable material, as set forth, the felt *b*, and the outer covering of textile fabric, the sleeve *w*, and means for securing the fabric to the pad, substantially as described.
